CLAIM

The ornamental design for a hair color kiosk, as shown and described.

DESCRIPTION

FIG. 1 is perspective view of the hair color kiosk;

FIG. 2 is front view thereof;

FIG. 3 is left view thereof;

FIG. 4 is back view thereof;

FIG. 5 is top view thereof; and,

FIG. 6 is a bottom view thereof.

The broken lines are for the illustrative purposes only and form no part of the claimed design.
